UNITED STATES PATENT OFFICE

TREVOR HUGH TURNER, OF LIVERPOOL, ENGLAND, ASSIGNOR TO AUTOMATIC ELECTRIC COMPANY, OF LIVERPOOL, ENGLAND, A BRITISH COMPANY

ELECTRICAL VOICE TRANSMISSION NETWORK

Application filed March 7, 1930, Serial No. 433,871, and in Great Britain March 8, 1929.

The present invention relates to the construction of a new form of transmission unit which is applicable both to filters for electrical networks which may be, for instance, of the type employed in connection with thermionic valve repeaters, or to cables used for transmitting current of speech frequency or carrier currents, and more particularly, applies to loaded cables.

10 It is well known that filters and loaded cables as usually designed give rise to what are known as transients, that is to say, disturbances which are produced when particular switching operations are effected. Wave filters are known in which the various sections have the same transition frequencies but have dissimilar impedance characteristics.

According to the invention all sections of the transmission unit have the same nominal impedance but adjacent sections have different transition frequencies. The advantages of a transmission unit according to the invention are firstly, that the transmission unit can be designed to present a sensibly constant impedance at its terminals over the entire range of transmission frequencies and possibly beyond. Secondly the transmission unit gives greater freedom from transients.

20 The invention will be better understood by referring to some extent to the theoretical considerations and also to the accompanying Figures 1-4, which figures will be best described in turn where they are referred to in the text.

In general the propagation constant of a section of a filter closed by its correct impedances is given by

$$40 \quad \text{Cosh } P = \frac{Z_1}{Z Z_2}$$

According to the invention Z_1 is changed from section to section by a factor which may or may not be a constant factor, while Z_2 is changed by a factor which is always the reciprocal of that for Z_1 .

Thus Figure 1 represents a convergent filter and a and b represent successive factors.

The co-efficients a and b may be chosen in any way for specific purposes. For example

the filter may converge to a certain point and afterwards diverge again. The cut off frequency of the two ends of the structure may even be different.

As an example, the invention may be applied to low pass filters in the manner illustrated in Figure 2.

It is assumed that it is required to design a low pass filter to give a cut-off frequency of 800 cycles, that is to say, that it will pass frequencies of less than 800 cycles and cut off higher frequencies. To do this a number of sections with cut-off frequencies starting from 1200 cycles and gradually reducing in steps of 100 cycles to 800 cycles in the middle are provided at each end. The number of sections of 800 cycles could be as many as desired. Now, the impedance of each section

$$70 \quad Z_0 = \sqrt{\frac{L}{C}}$$

The cut off frequency of each section is represented by the formula:

$$75 \quad f_c = \frac{1}{\pi \sqrt{LC}}$$

Hence it will be readily appreciated how the sections are to be calculated.

It will be understood that while it is assumed that the various sections have the same nominal impedance, this is by no means essential and it will be possible for the impedance as well as the cut-off frequency to be changed progressively, enabling the structure to operate between unequal impedances.

The invention could also be applied to band pass filters, in which case the outer sections would permit of the passage of a wide band of frequencies and successive sections would permit gradually reduced bands, the band towards the middle being the least and corresponding to the band of frequencies which the filter is designed to pass.

The reduction of transients with a filter according to the invention is based on the fact that these disturbances are due chiefly to phase delay differences. With a filter having sections all of the same cut-off frequency

or frequencies, the same delay is concentrated at or around certain definite parts of the range. With a filter embodying the principles of the invention, however, the delay will be distributed and thus the volume of the transient produced, for instance, by switching on, will be reduced.

An alternative design of filter within the scope of the invention to that just described 10 is one in which both the cut-off frequency and the nominal impedances of the section are varied together so that it becomes possible to construct a filter which, for a particular frequency, shall have no internal reflection losses (including dissipation) between adjacent sections.

By way of example of an application of the invention to a low pass filter, it may be assumed that it is desired to construct a low 20 pass filter to cut off 900 cycles and have a nominal impedance of 600 ohms. From the usual formula for regular filters

$$600 = \sqrt{\frac{L}{C}} \text{ and}$$

$$900 = \frac{1}{\pi \sqrt{LC}}$$

25 $L = .212 \text{ henry and}$
 $C = .59 \text{ mf.}$

The next step to make up sections for which

$$35 \frac{1}{\pi \sqrt{LC}}$$

becomes larger.

This may be done, for example, by taking 20% off .212 i. e. .1696. A further 20% off .1696 gives .1356 henry. The values of the 40 inductances should then be increased progressively in a similar manner.

In the present example C is so proportioned as to make the square root of L divided by C constant for each section, consequently the values of C are respectively .59 mf. 45 .472 mf. and .3776 mf. These would then be as shown in Figure 3.

Adjacent inductances could be combined into a single unit, for example:

50 The inductances $.106 + .085 = .191$ henry could be wound on a single spool or coil.

While we have shown adjacent sections having cut-off frequencies in constant ratio, the invention is not limited to this, the essential feature of the invention being that the cut-off frequency of the section changes from some value at one part of the filter to a different value at another part thereof. The 55 application to band-pass filters is similar, the band which is passed being wider at the ends than in the middle.

The invention is also applicable to a loaded cable. The usual arrangement of loading cables is to space the coils at even distances apart and allow for a certain amount of

tapering at the ends. This arrangement leads to transient effects which are more pronounced on long than on short lines. By applying the invention to a loaded cable a convergent cable can be obtained whose cut-off frequency varies from point to point, being lower at one point than at others. As an example a cable may have a low cut-off frequency in the middle or also at one end.

To reduce reflection losses the nominal impedance of the line should be made constant. At present, long lines are frequently lightly loaded so as to reduce transients giving a cut-off frequency of say 5,000 cycles. A cable 70 designed according to the invention would have a cut-off frequency which varied say from 3,000 cycles at the ends to 2,400 cycles in the centre.

The effect of having a high cut-off frequency at the ends would tend to give a more 85 gradual variation of impedances with frequency when considering impedances from the cable ends.

It is well known that transients or building up times are proportional to the slope of the wave length constant frequency curve, which 90 quantity is frequently called:

$$\frac{da}{d\omega}$$

Now, in a line which is loaded at regular intervals, the point of greatest wave length constant for each loading section occurs at the same frequency and the slope

$$\frac{da}{d\omega}$$

100 for the whole cable is a maximum. By making the cut-off frequency different for every loading section the slope would be greatly reduced.

One example of carrying out the invention will be described, giving the coil values and spacing for a typical line. It is necessary 110 in the first case to decide on the cut-off frequency of the end and centre sections.

Secondly, to decide on the type of taper, that is to say, whether the cut-off shall be in geometrical or arithmetical progression or 115 shall follow some other rule. The particular system employed is immaterial as concerns the invention itself.

Thirdly, to select the ratio of variation of cut-off frequency from one section to another, such that the cut-off frequency changes from one decided value to the other in half the length of the cable.

Fourthly, knowing now the cut-off frequency for each section, it is advisable to obtain the same value for

$$\sqrt{\frac{L}{C}}$$

120 for each section. Normally, the section may

be supposed to consist of two pieces of cable and one leading coil, or a portion of each two coils and the intermediate piece of cable.

Having followed these steps it becomes a comparatively simple matter to design each section, and the spacing and values of the coils can readily be determined.

It may at times be necessary to change both the cut-off frequency and the nominal impedance of a cable from one end to the other, to make the cable work in between two portions which have different impedances.

Referring to Figure 4, we have given an example of a cable with variable cut-off frequency. In this case the capacity of the length A B and the inductance of the coil L are decided by the required nominal impedance of the cable giving

$$\sqrt{\frac{L}{C}}$$

and the cut-off frequency of a particular section A B giving

$$\frac{1}{\pi \sqrt{LC}}$$

The impedance will be determined by the closest spacing possible which is permissible from the point of view of cost.

30 What I claim as new and desire to secure by Letters Patent is:—

1. A transmission element for audio frequency or like electric circuits comprising a number of sections, each section consisting of a wave filter having a different cut-off frequency, the cut-off frequencies of adjacent sections increasing progressively from a certain frequency.

2. A transmission element for electric circuits comprising a plurality of sections having the same nominal impedance, each section consisting of a wave filter having a different cut-off frequency, the cut-off frequencies of adjacent sections varying progressively from one end of the element.

3. An electric wave filter consisting of a line composed of a plurality of sections, each section having an inductance coil in series with the line and a condenser in shunt across the line, said inductance coils and condensers having precomputed values so proportioned that each section has the same nominal impedance but a different cut-off frequency than the adjacent sections.

4. A transmission element comprising a loaded cable divided into a plurality of sections, each section consisting of loading coils and a different precomputed length of cable so that the cut-off frequencies for adjacent sections vary progressively along the cable.

5. A transmission element comprising a loaded cable having loading coils spaced at different distances apart, said cable being divided into sections having the same nominal impedance, each section consisting of a

set of loading coils and a different length of cable so that the cut-off frequencies of adjacent sections vary in a predetermined manner.

6. A transmission element comprising a loaded cable, loading coils spaced at different distances apart in said cable dividing it into sections, each section consisting of a set of loading coils and a different length of cable, the cut-off frequencies of adjacent sections varying progressively from each end to the center of the element.

In testimony whereof I affix my signature.
